COMBINED MAILING AND RETURN
ENVELOPE

Harry Elbaum, New York, N. Y.

Application September 5, 1934, Serial No. 742,746

1 Claim. (CL 229—73)

This invention relates to new and useful improvements in mailing devices and more particularly it pertains to a new and improved combination mailing and return envelope.

5 It is an object of the invention to provide a combined mailing and return envelope which may be constructed from a single blank of material, whereby a minimum amount of material is required.

10 It is a further object of the invention to provide a device of the above mentioned character in which the two envelopes are secured to each other until such time as it is desired to use the return envelope for mailing purposes.

15 It is a still further object of the invention so to construct the envelopes, that one of them is adapted to be folded into the other in the manufacture of the device, which position it occupies until such time as it is ready for use when it may be removed from the outer envelope and detached therefrom.

20 Other objects will appear as the nature of the invention is better understood and reference will be had to the following specification and the accompanying drawing, wherein,

25 Figure 1 is a plan view of a blank from which a mailing device constructed in accordance with the present invention may be formed.

Figure 2 is a plan view showing the two envelopes completely formed before they are folded one into the other,

30 Figure 3 is a plan view showing the envelopes folded one into the other, the device not being sealed,

35 Figure 4 is a view similar to Figure 3, with one of the envelopes folded to position within the other,

Figure 5 is a sectional view taken substantially on the line 5—5 of Figure 4, and

40 Figure 6 is a sectional view taken substantially on the line 6—6 of Figure 3.

45 Referring more specifically to the drawing, A, designates a blank of suitable material, preferably paper, from which the device is formed. The blank is perforated, scored, creased or otherwise weakened along a transversely extending line 16, which line divides the blank into two sections, 11 and 12.

50 From the section 11, I form the mailing envelope and from the section 12, I form the return envelope and I will now proceed to describe the manner in which these two envelopes are formed.

55 Extending from one of the marginal edges of the section 11, there is an extension 14, which forms the sealing flap of the mailing envelope

when the blank is folded along the line 15. Projecting from another marginal edge there is an extension 16 which folds inwardly of the section 11 on the line 17, and which together with the extension 18, which folds inwardly of the section 11 upon the line 19, forms the back of the mailing envelope. These extensions 16 and 18 are shown in their infolded positions in Figure 2, and it will be noted that in these positions, the extension 18 overlies the extension 16. A suitable adhesive 20 10 is employed to secure the flaps 16 and 18 in overlapped relation. The sealing flap 14 bears adhesive 21 by which it may be sealed closed.

15 Projecting from one of the marginal edges of the section 12 there is an extension 30 which, when folded upon the line 31, forms a sealing flap for the return envelope. Projecting from the opposite marginal edge of the blank 12 there is an extension 32 which, when folded upon the line 33, forms the back or rear wall of the return 20 envelope. Opposite edges of the extension 32 25 may be provided with adhesive as designated at 34 and 35. The adhesive 34 and the adhesive 35 form the means by which the extension 32 may be secured to the section 12 to form the return 25 envelope. The sealing flap 30 is provided with adhesive 36 by which it may be sealed closed.

30 In forming the mailing device from the blank shown in Figure 1, the two extensions 16 and 18 of the section 11, are folded inwardly and secured together as heretofore described and the extension 32 is folded inwardly of the section 12 and secured thereto. The device will then appear as it is shown in Figure 2. It will be noted by examination of the drawing that the section 12 is slightly 35 narrower than the section 11, the line of fold 32 being slightly out of line with its respective line of fold 15, as indicated at 41 in Figure 2.

35 By this construction, the return envelope which is formed from the section 12, will be slightly 40 smaller than the mailing envelope in order that it may be received therein, and it is this position which the return envelope occupies in the finished form of the device. To position the return envelope within the mailing envelope, the blank is 45 folded upon the line 16, and the device appears as illustrated in Figure 3.

Figure 3 illustrates the complete device ready for use and in use, a letter, circular or the like is inserted into the mailing envelope along with 50 the return envelope and the sealing flap 14 of the mailing envelope is sealed closed for mailing.

The recipient removes both the enclosure and the return envelope upon opening of the mailing envelope and if he desires to use the return en- 55

velope, he merely detaches it along the line 10, whereupon it is free for use.

By examination of Figure 4 of the drawing, it will be apparent that a portion 45 of the return envelope is visible at the rear of the mailing envelope and that in reality, the return envelope forms the back of the mailing envelope when it is in position within the mailing envelope.

It will also be noted that the front face of the 10 return envelope is presented to the under side of the sealing flap 14 of the mailing envelope when the return envelope is in position within the mailing envelope. This is important, since 15 it protects the sealing flap of the return envelope against damage by an instrument inserted beneath the sealing flap of the mailing envelope to open the mailing envelope.

While the invention has been herein illustrated in its preferred form, it is to be understood that 20 the invention is not to be limited to the specific form in which it is shown and that it may be practiced in other forms without departing from the spirit thereof.

Having thus described the invention, what is claimed as new, is:

A combined mailing and return envelope comprising two individual envelopes formed of a single blank, each of said envelopes including a body and flap portions, said mailing envelope being larger for receiving the return envelope, the body portions of said envelopes being connected along one edge and provided with a row of perforations forming both the line of severance and line of fold of said envelopes for folding the return envelope in the mailing envelope, one of the flaps of said return envelope being sealed adjacent the line of perforations, the flaps of the mailing envelope cooperating when folded upon 15 its body to cover the major portion of the return envelope and to seal the same in the mailing envelope, the uncovered portion of the return envelope providing a finger gripping area to facilitate its removal in unsevered condition upon the 20 opening of either the top or bottom flaps of the mailing envelope.
